US00D515520S

(12) **United States Design Patent** (10) Patent No.: **US D515,520 S**
Komoto (45) Date of Patent: **** Feb. 21, 2006**

(54) **SEMICONDUCTOR DEVICE**

(75) Inventor: **Satoshi Komoto**, Tokyo (JP)

JP 751629 12/1988
JP 865628 4/1993

(73) Assignee: **Kabushiki Kaisha Toshiba**, Tokyo (JP)

(**) Term: **14 Years**

(21) Appl. No.: **29/168,222**

(22) Filed: **Sep. 30, 2002**

(30) **Foreign Application Priority Data**

Mar. 29, 2002 (JP) 2002-008490

(51) LOC (8) Cl. **13-03**

(52) U.S. Cl. **D13/182**

(58) **Field of Classification Search** D13/182;

174/52.1, 52.4; 257/666, 669, 675, 676, 678,

257/690, 692, 696, 697, 730, 787; 361/773,

361/820; 438/64, 65

See application file for complete search history.

(57) **CLAIM**

The ornamental design for a semiconductor device, as shown and described.

DESCRIPTION

FIG. 1 is a front, top and right side perspective view of a semiconductor device, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.
